UNITED STATES PATENT OFFICE.

GEORGE CROUCH, OF NEW YORK, N. Y.

DESIGN FOR A TRUNK-ROLLER FRAME.

SPECIFICATION forming part of Design No. 27,547, dated August 17, 1897.

Application filed April 6, 1897. Serial No. 631,032. Term of patent 7 years.

To all whom it may concern:

Be it known that I, GEORGE CROUCH, a citizen of the United States, residing at the city, county, and State of New York, have invented 5 and produced a new and original Design for Trunk-Roller Frames, of which the following is a specification.

In the accompanying drawings, Figure 1 is a plan view, and Fig. 2 is a side view.

10 The leading feature of this design consists in a straight top plate having two openings through it and plates crossing the openings and flat on their top edges and rounding on their lower edges.

The plates *b c d* are parallel and straight on 15 their upper edges and curved on their lower edges, and the straight top plates *e f* extend out from the ends of the plates *b c d*, as shown.

I claim—

The design for the trunk-roller frame, as 20 herein shown and described.

Signed by me this 1st day of April, 1897.

GEO. CROUCH.
